UNITED STATES PATENT OFFICE.

CLYDE E. COCHRAN, OF CLEVELAND, OHIO, ASSIGNOR TO THE ELWELL-PARKER ELECTRIC COMPANY, OF CLEVELAND, OHIO, A CORPORATION OF OHIO.

INDUSTRIAL TRUCK.

Application filed January 25, 1923. Serial No. 614,720.

To all whom it may concern:

Be it known that I, CLYDE E. COCHRAN, a citizen of the United States, residing at Cleveland, in the county of Cuyahoga and State of Ohio, have invented a certain new and useful Improvement in an Industrial Truck, of which the following is a full, clear, and exact description, reference being had to the accompanying drawings.

This invention is concerned with industrial trucks of the type wherein power means is provided for driving the truck when transporting loads, and is particularly concerned with that class of trucks known in the art as "tier lift trucks".

In trucks of the character referred to, it has been customary to provide a load lifting platform supported on elevating mechanism carried by an upright frame, there being power means to elevate a load only a sufficient distance to transport the load or to elevate the load to greater heights whereby it may be stacked or transferred to another vehicle. The lifting mechanism on such trucks has usually comprised vertically disposed screw members engaging a nut fixed to and movable with the elevating platform or a cable and winding mechanism.

It has been found however, that a truck equipped with a screw elevating platform, when used during a considerable period, for merely elevating a load to clear the supporting surface of the truck results in a wear or deterioration of that portion of the screw member which is thus repeatedly acting on the nut secured to the platform. A subsequent use of the truck for raising a load to a greater height, results in a distortion of the screw member due to a binding action between the screw member and the worn and distorted nut. This objection is characteristic of both single and double screw lift arrangements.

It has also been found impractical to use a single cable directly connected to the elevating mechanism, as the possibility of the cable breaking and thereby permitting the load to drop, with a consequent damage or destruction of the truck frame, is always present. Furthermore, with the use of a double cable arrangement directly connected to the elevating mechanism, a distortion

or straining of the load elevating mechanism results as one cable will usually stretch more than the other.

Therefore, the general object of the present invention is the provision of a commercially practical automotive industrial truck which is readily adaptable to the lifting and transporting of heavy loads on a load lifting platform and which may also be utilized to elevate and stack the loads.

More specifically, my invention is concerned with the provision of a novel, heavy duty power operated load lifting mechanism which may be embodied in an industrial truck in such manner as to eliminate the foregoing discussed objectionable characteristics of present-day tier lift constructions.

An additional object of the present invention is the provision of a cable winding mechanism adaptable for use in a tier lift truck and which may be provided with separately acting flexible members actuating the load lifting members through a torque equalizing mechanism whereby buckling or straining of the load lifting mechanism by any uneven stretching of the respective cables is prevented.

A further object of my invention is to embody the means for fulfilling the foregoing described objects in a power actuated, tier lift truck having universal characteristics of load lifting, transporting and stacking, provision being made for controlling the tiering mechanism from an operator's position on the truck.

Other objects will become apparent from the following description taken in connection with the accompanying drawings and the essential features will be summarized in the claims.

In the drawings, Fig. 1 is a side elevation of an industrial tier lift truck embodying the various features of my invention; Fig. 2 is a plan view of the truck; Fig. 3 is an enlarged cross sectional elevation of the truck taken substantially along the line 3-3 of Fig. 2; Fig. 4 is a side elevation of the rear portion of the truck; Fig. 5 is an enlarged cross sectional view taken substantially along the line 5-5 of Fig. 1; Fig. 6 is a cross-sectional view taken substantially along the line 6-6 of Fig. 5; Fig. 7

is a detail cross sectional view showing a gear drive of the winding mechanism corresponding to a section taken along the line 7—7 of Fig. 2; and Fig. 8 is a cross sectional view taken substantially along the line 8—8 of Fig. 2 and showing a solenoid brake mechanism acting on the armature shaft of a winding motor.

Designating the various members and elements comprising the truck, in Figs. 1 and 2, I show a truck frame comprising side frame members 10 preferably formed of castings, and a rearwardly extending frame member 11 secured thereto and formed to afford attachment for small rear steering wheels 12 and suitable steering mechanism (not shown). Attached to the forward side frame members 10, are power driven wheels 12^a, the wheels being driven through suitable reduction gearing by a motor supported on the forward end of the truck. Upright angle members 13 and 14 may be attached to the side members 10 and to an intermediate supporting frame 9 comprising a support for a battery housing 15. Parallel members 16 provide floating engagement between the truck frame and the front axle housing. Provision for controlling movement of the truck from an operator's platform which may be attached to the forward end of the truck may be made in a manner well known in the art.

The construction of the frame, wheels, housing, etc. above mentioned, does not enter into the present invention; they may however be formed according to the disclosure set forth in my Patent No. 1,260,145 granted March 1918 to the Elwell-Parker Electric Company as my assignee.

The load lifting means extends over the rear end of the truck frame and is supported by a vertically extending structure disposed intermediate the forward and rearward end of the truck. This structure may comprise channel members 18 secured to the truck frame members 10 with the flanges thereof extending inwardly. These channel members are spaced apart a sufficient distance to provide a vertical support for L-shaped load lifting members 20 which ride thereon and coact therewith in a manner to be presently described.

The channel members extend a substantial distance above the top surface of the battery housing 15 and are braced intermediate the top and bottom ends thereof by angle members 21 and 22 secured to the battery housing frame and to the side faces of the channel members. A transverse top member 24 preferably comprising a casting may be secured to the upper ends of the channel members and serve as a spacing means therefor as well as a supporting beam for cable sheaves 23.

A removable load supporting platform 66 19 is detachably secured to and carried by the arms 20 and is of sufficient length to extend a substantial distance rearwardly over the small wheels 12 and is likewise of sufficient width to laterally cover these 70 wheels when the arms 20 are in a lowermost position. Suitable bearing bosses 20^c may be formed on the arms to engage flat members 19^a secured to the under side of the platform 19. 75

To provide efficient sliding engagement between the load lifting members 20 and the upright frame, as well as to obtain a favorable cantilever reaction upon the frame when the arms 20 are carrying heavy loads, 80 I have mounted roller members 25 adjacent the upper ends of vertically extending portions 20^a of the arms 20, and similar rollers 28 on studs fixed to the lowermost portion of the arms. The arms 20 are provided with 85 integral extensions 20^b affording a support for the rollers whereby the rollers may engage the channel members of the frame. A bar member 26 extends through the arm portions 20^a and affords lateral bracing of 90 the arms and provides a suitable mounting for the rollers 25. The rollers 25 as will be seen in Fig. 4, are disposed on one side of the channels while the rollers 28 are disposed on the opposite side of the 95 channels and engage the upright frame along track members or strips 18^a secured to the forward and rearward flanges of the channels 18 by screw members 19.

If desired, the rollers may be formed in 100 the manner shown in Fig. 5 with flanges 29 engaging the beveled side faces of the track bars 18^a and may be hollow to receive anti-friction means comprising a bearing member 30 rigidly mounted on the outer 105 ends 26^a of the bar member 26. The bearing member 31 is rigidly secured to the roller 25 by a removable cap member 32. A similar bearing construction may be provided for the lower roller members 26. 110

It will be noted that the spaced apart and staggered relation of the rollers 25 and 28 to the channel members 18 affords the maximum beam strength of the channel members comprising the upright frame in resisting 115 bending moments due to the lifting of heavy loads. A sleeve member 33 is positioned on the bar member 26 and abuts the bearing portions 20^b of the arms 20 and thus prevents displacement or disarrangement of the 120 lateral relation to the load elevating arms.

The arms 20 are preferably actuated by a motor driven winding mechanism 49 positioned on the top of the battery housing acting on a second winding mechanism carried 125 by the arms 20; the latter mechanism actuating pinions 35 disposed within the flanges of the channel members 18. These pinions en-

gage vertically extending rack bars 36 secured to the inside of the front flanges of the channel members 18. The two winding mechanisms are connected by a pair of cables 50, the arrangement of the winding mechanism carried by the load elevating arms being such, that the lifting effect of either cable is equally distributed to the pinion members 35. By providing cables of sufficient strength whereby either cable may suspend the load without causing unbalanced stresses in the upright frame or load lifting frame, I eliminate the disadvantages of a double cable hoist.

15 The means for distributing the reactive forces of either or both cables will now be described.

As shown in Fig. 5, the pinions 35 are provided with inwardly extending hub portions 35^a which are journaled in bearing portions forming the upper ends of the arms 20. The pinions 35 are in rigid engagement with a transversely extending shaft member 41 which comprises a support for a pair of cable drums 42 rotatably mounted thereon. Disposed between the drum members and rigidly fastened to the shaft, is a spider member 43 comprising a bearing for differential pinions 44, preferably three in number, which engage bevel gear teeth 45 formed on the end walls 42^b of the drum members 42.

The operation of this differential arrangement is as follows:—When the arms 20 are in their lowermost position, the grooves of the drum are completely filled with stretches of cables 50 wound thereon, the drums being of sufficient diameter to receive stretches of cables of such length as to correspond to the full vertical travel of the load lifting mechanism. Taking in or winding up of the cable stretches 50 by the winding mechanism disposed on the battery housing, causes an unwinding of corresponding portions of the cables disposed on the drums 42, thus effecting a rotation of the drum members and rotation of the shaft 41. The pinions thus move along the rack bars 36 and an upward movement of the elevating mechanism is effected. If the load is light and the quality 50 of the cables 50 is uniform throughout, there will be practically no movement of the differential pinions 44, the differential pinions merely acting as a connection between the beveled teeth 45 on the drums and the spider member 43 rigid with the shaft 41. If however, there is an unequal relative stretching of the cables 50, there will be a relative movement between the drums which will be compensated by the differential pinions 44. 60 The same degree of stress is thus exerted on each of the cables 50 when the load is being raised. Adjacent flanges 42^b of the drum members are provided with projections or lugs 46 which move in a path represented 65 by the space indicated at 47, and in the event

either cable breaks, the drums will become interengaged when the lugs engage each other. The drum members 42 are placed upon the shaft 41 with the lug members 46, disposed substantially 180° apart as shown 70 in Fig. 6, and are thus movable through substantially one-half revolution relative to each other before they engage. Either cable may thus stretch a distance corresponding to a one-half drum turn thereof before the 75 proper balancing of the load on the cables would be interfered with.

The winding mechanism disposed on the battery housing as hereinbefore stated may be motor actuated and may comprise a motor 49 having the casing thereof supported by a frame 51 secured to the top surface of the battery housing. The frame 51 may support a second pair of cable drums 52 which act upon the cable stretches 50. 80 85

The cable stretches 50 extend upwardly in a substantially vertical direction from the load lifting mechanism and over the sheave members 23, the latter members being supported by a bar 54 rigidly mounted on downwardly extending bracket portions 22^a formed on the top frame member 22. These bracket portions 22^a are spaced apart a sufficient distance to permit a transverse shifting of the sheaves 23 as the cable stretches 50 move transversely due to the winding action of the drums. 90 95

The winding drums 52 are driven by the motor 49 through suitable reduction gearing which may comprise a bevel pinion 56 mounted on a shaft 57 journaled in the frame 51 and connected to the armature shaft 49^a of the motor by a flexible coupling 58. The pinion 56 engages a bevel gear 60 which is mounted on a sleeve 61, the latter member engaging a shaft 62 carrying a worm 63. The bevel gear 60 and shaft 62 may be provided with anti-friction bearings as indicated at 64 and 65 respectively. The worm gearing comprises a worm wheel 66 fastened to the drum shaft 67. All of the foregoing described reduction gearing may be suitably housed by a casing 51^a forming part of the frame 51. 100 105 110

To arrest rotation of the motor immediately upon disconnection of the power, I provide a suitable brake, shown as comprising a friction disc 70 secured to the armature shaft 49^a of the motor 49, a cup-shaped frame 71 rigid with the frame of the motor 49 and a magnetically shiftable disc member 72. Rotation of the disc member 72 is prevented by engagement with pin members 73 which are rigid with the member 71. Spring members 74 are maintained in position by the pin members and are disposed between the disc 72 and the housing member 71. Suitable magnetic coils 75 may also be supported by the housing member 71, the electrical connections thereof being such that 115 120 125 130

the coils may be connected in series with the armature of the motor. Anti-friction means 76 may be secured to either rotating disc member 70 or the magnetically actuated plate 72. The deenergizing of the motor, deenergizes the coil 75 which is acting in opposition to the spring members 74. The spring members thus urge the disc members 72 outwardly and compress the anti-friction band 76 against the rotating face of the disc member 70 and the rotation of the armature of the motor is immediately arrested, thus preventing an undesirable over movement of the winding drum and load elevating mechanism.

It is desirable that the control means for the winding motor 49 be located adjacent the driver's position on the truck. It is also desirable that the controller means be associated with means automatically operated upon an extreme upper or lower movement of the load elevating mechanism to automatically stop the winding motor. The latter means may be embodied in a mechanism such as has been disclosed for a similar purpose in the Towson Patent No. 1,238,824, issued July 17, 1917, which discloses a mechanism adapted to be actuated upon an extreme movement of a load lifting platform on an industrial truck and to control a motor actuating the platform. I accordingly provide a double switch, as indicated at 80 which may be disposed on the truck beneath the battery housing 15; suitable electrical connections (not shown) extending from the battery to the switch and from the switch to the motor may serve to connect the battery of the vehicle to the motor.

Such a switch mechanism 80 may comprise a double contact blade 81 carried by a rocker arm 82 which may be manually operated by a control lever 83 disposed on the forward end of the truck adjacent the driver's position. A bell crank 84 is connected to the lever 83 by a rod member 85 and to the switch arm 82 by a link member 87. An upward or a downward movement of the control lever 83 will cause the motor to drive the winding mechanism in an unwinding or winding direction respectively.

Slidably mounted adjacent the forward end of the vertical frame structure, is a switch actuating member 90 carrying adjustable stop members 90^a which are mounted on the member 90 in such manner as to be engaged by the sleeve 33 of the load lifting frame upon an extreme upward or downward movement of the load lifting platform. The switch blade 81 is thus shifted to a neutral position out of engagement with the contacts 81^a. The rod member 90 is connected to the switch 80 through a bell crank member 91 and a connecting rod 92 which is preferably connected to a bell crank member 84 mounted on the forward end of the truck.

Spring members 94 are mounted on the rod 92 to oppose each other and to engage a plate 95 rigidly mounted on the truck frame whereby the switch mechanism 80 is maintained in a normally open condition. The winding mechanism will therefore be active only when the switch mechanism is manually maintained closed by the operator holding the lever in an upward or downward position.

It will thus be seen that the load lifting mechanism may be controlled from the forward end of the truck which is preferably the operator's position, there being a standing platform for the operator (not shown) adapted to be mounted on bracket members 10^a rigidly secured to the truck frame.

Many advantages may be found in the embodiment of my invention in a heavy duty automotive truck among which are:— the use of more than one flexible member or cable to elevate the load engaging means without the disadvantage or annoyance of having to continually adjust the mechanism to maintain an equal load on each of the cable members, the load lifting mechanism being such as to automatically fulfill this purpose; the obtaining of a commercially practical heavy duty truck of ordinary size whereby the floor space required for the movement and operation of the truck is not unusual while at the same time obtaining an extraordinary lifting capacity in this character of truck; and the elimination of the possibility of damage to the truck frame in the event one of the cable members should break. Furthermore, the reacting forces between the upright frame and the load lifting mechanism are such as to contribute to the ultimate lifting force exerted upon the load when the same is being elevated.

I claim:—

1. In an industrial truck, the combination of a motor driven winding mechanism rigidly fixed relative to the truck frame, an upright frame structure, a second winding mechanism actuated by the first named mechanism and relatively movable thereto, a load lifting support movable with the second winding mechanism, flexible members associated with both of the winding mechanisms and reacting on said upright frame structure, whereby the winding action of the motor driven winding mechanism upon the flexible members will effect an unwinding action of the second named winding mechanism and impart movement to the load support while being guided by the upright frame structure.

2. In an industrial truck, the combination of a power-operated winding mechanism rigidly mounted on the truck, an upright frame structure, a second winding mechanism relatively movable thereto and actuated thereby, stretches of cable asso-

ciated with the respective winding mechanisms and extending over the frame structure, a load support movable with the second named winding mechanism whereby a taking-in action of the cables by the power-operated winding mechanism will effect the second named winding mechanism in such manner as to pay out the cable and result in the imparting of movement to said load support along said upright frame structure.

3. In an automobile truck, the combination of an upright frame rigid with the frame of the truck, a load lifting frame 15 guided by the upright frame and relatively movable thereto, a power-operated winding mechanism secured to the frame of the truck, a second winding mechanism mounted on one end said load lifting frame adjacent the upright frame, and power transmitting means connecting the two winding mechanisms whereby operation of the winding mechanism on the truck frame will cause the second named winding mechanism 25 to elevate or lower said load lifting frame.

4. In an industrial truck having power-driven wheels, the combination of a vertically extending frame rigid with the frame structure of the truck, a power-operated 30 winding mechanism mounted on the truck, a load lifting mechanism mounted on the upright frame including pinions cooperating with racks on the upright frame and adapted to traverse the length thereof, including 35 a winding mechanism mounted thereon and actuated by said first named winding mechanism to actuate the pinions and torque equalizing means operatively disposed between the pinions and said last named winding mechanism.

5. In an automotive industrial truck, the combination of an upright frame structure rigid with the frame of the truck, and load elevating mechanism movably mounted on 45 said upright frame structure comprising a load carrying platform, outwardly extending members engaging the upright frame structure and supporting the platform, and actuating mechanism including cable drums, 50 rack bars rigid with the upright frame structure, pinions rotatably mounted on the load elevating mechanism and torque equalizing means connecting said pinions and drums whereby the load on said drums may 55 be equalized when raising a load.

6. In an industrial truck having power-driven wheels, the combination of a vertically extending frame rigid with the frame structure of the truck, a power-operated 60 winding mechanism mounted on the truck, a load lifting mechanism mounted on the upright frame and adapted to traverse the length thereof, including a winding mechanism, an unwinding action of which effects 65 an elevating movement of the load lifting

mechanism and flexible members connecting the two winding mechanisms and extending over the upright frame structure.

7. In an automotive industrial truck, the combination of an upright frame structure 70 rigid with the frame of the truck, a load elevating mechanism movably mounted on said upright frame structure, a winding mechanism on the truck, and actuating mechanism including rack bars rigid with 75 the upright frame structure, flexible members connecting said winding and actuating mechanisms, pinions rotatably mounted on the load elevating mechanism and engaging the rack bars and reactive means engaging 80 the upright frame structure and serving to maintain the pinions in meshing relation with the racks.

8. In an industrial truck, the combination 85 of an upright frame structure rigid with the frame of the truck, a load lifting mechanism movably mounted on the upright structure, a winding mechanism mounted on the truck frame including a pair of cable winding drums, cables connecting the winding mechanism with the load lifting mechanism, drums therefor and compensating means including gears connecting the winding mechanism to the load lifting mechanism whereby an equal tension may be exerted on each cable when there is an uneven stretching of the cables during a load lifting operation.

9. In a truck, the combination of an upright frame structure rigid with the frame 100 of the truck, a load lifting mechanism movably mounted on said upright frame, and actuating mechanism including rack bars, pinions engaging the rack bars, relatively movable elements, and torque equalizing means 105 drivingly connecting the elements to the pinions whereby the actuating mechanism will cause the elements to be equally effective in moving the load lifting mechanism.

10. In a truck, the combination of upright frame members rigidly secured to the frame of the truck, a load elevating mechanism, rack bars mounted on the upright frame members, power-operated means for actuating the load lifting mechanism comprising gear members coacting with the rack bars and rotatably mounted on the load lifting mechanism the reactive means 115 movably embracing the upright members to maintain the gears and bars in meshing relation and power-operated winding drums actuating said gear members.

11. In an industrial truck, the combination 120 of a motor driven winding mechanism rigid relative to the truck frame, a second winding mechanism actuated by the first named mechanism and relatively movable thereto, a load lifting support movable with the second winding mechanism, flexible members associated with both of the wind- 125 130

- ing mechanisms, whereby the winding action of the motor driven winding mechanism upon the flexible members will effect an unwinding action of the second named winding mechanism and impart movement to the load support, and torque equalizing means embodied in the second named winding mechanism to cause the flexible members to be equally loaded.
12. In an industrial truck, the combination of a power-operated winding mechanism rigidly mounted on the truck, a plurality of cables actuated by the winding mechanism, a load support moved by the cables and a differential gear mechanism equalizing the load on the respective cables.
13. In an industrial truck having a frame and power driven wheels, the combination of an upright frame rigid with the truck frame, a power-operated winding mechanism mounted on the frame of the truck, a load lifting support movably mounted at one end on the upright frame, a second winding mechanism mounted on the support adjacent the upright frame and actuated by said first named winding mechanism and roller members engaging the upright frame and arranged to take the reaction caused upon movement of the second named winding mechanism along said upright frame.
14. In an industrial truck, the combination of a power-operated winding mechanism rigidly mounted on the truck, a motor therefor, an upright frame also rigidly mounted on the truck, a load lifting mechanism associated with said upright frame, a second winding mechanism active to move the load lifting mechanism, each of said winding mechanisms including cable drums and cables associated therewith in such manner that a winding action of the drums of one of the winding mechanisms effects an unwinding action of the drum corresponding thereto included in the second named winding mechanism and thereby imparts movement to the load lifting platform and torque equalizing means operatively disposed between the drums.
15. In an industrial truck, a power driven winding mechanism rigidly mounted on the truck, an upright frame rigid with the truck frame, a load lifting support movably mounted on the upright frame, a second winding mechanism associated with the support and active to raise the support during an unwinding action thereof effected by a winding action of the power-operated winding mechanism, cable members extending over the upright frame structure, and drums included in each of the winding mechanisms adapted to act on the cables whereby a winding action on the cable of the drum of one of the winding mechanisms will cause an unwinding action of one of the drums of the other winding mechanism and thereby im-
- part movement to the load support and torque equalizing means between the drums.
16. In an industrial truck of the character described, a motor driven winding mechanism mounted on the truck, an upright frame also mounted on the truck, a load lifting platform associated therewith and relatively movable thereto, a winding mechanism associated with the load lifting platform, cable members connecting the respective winding mechanism and a platform actuating mechanism associated with the second named winding mechanism and the upright frame including rack members and gear members associated therewith and reactive means engaging the frame structure and serving to maintain the rack and gear members in cooperative relation.
17. In an industrial truck of the character described, an upright frame structure rigidly mounted on the frame of the truck, load lifting means associated therewith including an elevating platform, rack bars rigidly mounted on the upright frame structure, gear members coacting therewith and movable with the platform, power driven means rigidly mounted on the truck, power transmitting means associated with said last named means and with the load platform to impart rotation to said gear members associated therewith, whereby said gear members coact with the rack members to raise and lower said load lifting platform and means mounted on the load lifting platform for maintaining the rack and gear members in cooperative relation when the platform is moved.
18. In an automotive truck of the character described, the combination of a power-operated winding mechanism rigidly mounted on the truck, an upright frame structure also mounted on the truck, a load lifting platform associated with the upright frame structure and relatively movable thereto, a winding mechanism movable with the platform and having a pair of independently rotatable cable drums, there being a pair of relatively non-rotatable cable drums included in the first named winding mechanism, cable members connecting the corresponding drums of the respective winding mechanisms, a shaft member rotatably supporting the drums of the second named winding mechanism, and gearing means associated with the platform of the upright frame structure driven by either of said drums, and torque equalizing means connecting the drums to said shaft whereby the cables associated with either of the drums may be effective in imparting movement to said gearing mechanism and the load lifting platform.
19. In an industrial truck of the character described, the combination of an upright frame structure rigid with the frame struc-

ture of the truck including rack members, a load lifting mechanism associated with the upright frame structure, power-operated means also mounted on the truck, said load lifting mechanism including gear members disposed on opposite sides thereof adjacent the sides of the upright frame structure, cable drums associated with said gearing, and flexible cable members arranged to be wound 5 on said drums and associated with said power-operated means, whereby a drawing in of the cable members by said power-operated means will unwind the cables from said drums and cause an elevating movement 10 of said load elevating mechanism, and a paying out of the cables by said means will permit said drums to rewind the cables during a lowering movement of said load elevating means and means movable with the 15 load elevating means for maintaining the gears in meshing relation with the racks.

20. In an automotive truck of the character described, the combination of an upright frame rigid with the frame of the truck, a cable winding mechanism having a plurality of drums, a load lifting frame associated with said upright frame structure, a pair of independently revolable drums rotatably mounted on said load lifting frame, actuating means operable to cause said load lifting frame to traverse the length of the upright frame structure, and means disposed between said drums to cause inter-engagement thereof after a predetermined independently revolving movement therebetween.

21. In an industrial truck, a power driven winding mechanism rigidly mounted on the truck, an upright frame rigid with the truck frame, a load lifting support movably mounted on the upright frame, a second winding mechanism associated with the support and active to raise the support during an unwinding action thereof effected by a 45 winding action of the power-operated winding mechanism, cable members, drums included in each of the winding mechanisms adapted to act on the cables whereby a winding action on the cable of the drum of 50 one of the winding mechanisms will cause an unwinding action of one of the drums of the other winding mechanism and thereby impart movement to the load support, and means cooperating with each of the drums 55 for equalizing the load on each of the cable members.

22. In an industrial truck, the combination of a power-operated winding mechanism rigidly mounted on the truck, a motor therefor, an upright frame also rigidly mounted on the truck, a load lifting mechanism including roller members engaging the forward and rearward portions of the upright frame, a second winding mechanism active to move 60 the load lifting mechanism, each of said

winding mechanisms including cable drums and cables associated therewith in such manner that the reaction of unwinding the cables from the drums is taken up by the upright frame through said rollers.

23. In an industrial truck of the character described, a motor driven mechanism mounted on the truck, an upright frame also mounted on the truck, a load lifting platform associated therewith and relatively 75 movable thereto, a second winding mechanism associated with the load lifting platform, cable members connecting the respective winding mechanisms, a platform actuating mechanism associated with the second 80 named winding mechanism and the upright frame including rack members on the frame and gear members movable with the load lifting platform and means for equalizing the load on the cable members and on the 85 gear members.

24. In an industrial truck of the character described, an upright frame structure rigidly mounted on the frame of the truck, load lifting means associated therewith including an elevating platform, and a plurality of cable members, rack bars rigidly mounted on the upright frame structure, gear members coaxing therewith and movable with the platform, power means rigidly mounted on the truck and actuating the cable members, and the load platform and torque equalizing means drivingly disposed between the gear members and the cable members whereby each of the cable members 90 may be effective in actuating said gear members.

25. In an automotive truck of the character described, the combination of power-operated winding mechanism rigidly mounted on the truck, an upright frame structure also mounted on the truck, a load lifting mechanism associated with the upright frame structure and relatively movable thereto, cable members connecting the winding mechanism with the load lifting mechanism, and a differential gear means equalizing the load on the cable members.

26. In an industrial truck of the character described, the combination of an upright frame structure rigid with the frame structure of the truck, a load lifting mechanism associated with the upright frame structure, power-operated means also mounted on the truck, said load lifting mechanism including gear members disposed on opposite sides thereof adjacent the sides of the upright frame structure, and rack bars rigid with the upright frame, a cable drum associated with said gearing and rotatably mounted on the load lifting mechanism, a flexible cable member arranged to be wound on said drum and actuated by said power-operated means, whereby a drawing in of the cable by said 100

8 power-operated means will unwind the cable from said drum and cause an elevating movement of said load elevating mechanism and anti-friction roller members movable with the load lifting mechanism for maintaining the rack and gear members in mesh.

27. In an automotive truck of the character described, the combination of an upright frame rigid with the frame of the truck, a cable winding mechanism having a plurality of drums, a load lifting frame associated with said upright frame structure, a pair of independently revoluble drums rotatably mounted on said load lifting frame, frame actuating means operable to cause said load frame to traverse the length of the upright frame structure, including a pair of cables, and means causing said drums to become relatively non-rotatable whereby either of said cables may be effective in elevating said load lifting frame.

28. In an industrial truck, the combination of an upright frame structure rigid with the frame of the truck, a load lifting mechanism movably mounted on the upright structure, a winding mechanism mounted on the truck frame, cables connecting the winding mechanism with the load lifting mechanism, and power equalizing means interposed between the winding mechanism and the load lifting mechanism for evenly distributing the load on the cables.

29. In an industrial truck, the combination of an upright frame structure rigid with the frame of the truck, a load lifting mechanism movably mounted on the upright structure, a winding mechanism mounted on the truck frame, cables connecting the winding mechanism with the load lifting mechanism, rack bars on the upright frame, gear members engaging the rack bars and movable with the load lifting mechanism, and means for evenly distributing the load lifting force of the cables to said gears.

30. In a truck, the combination of an upright frame structure rigid with the frame of the truck, a load lifting mechanism movably mounted on said upright frame structure, comprising members extending outwardly from the upright frame structure and adapted to support a load, and actuating

mechanism including rack bars rigid with the frame structure, a shaft member rotatably mounted on said load supporting members, a plurality of drums rotatably mounted on the shaft member, torque equalizing means connecting the shaft member and the drums, and pinions mounted on the shaft member and engaging said rack bars, whereby actuation of the shaft member will cause the pinions to be effective in moving the load supporting members.

31. In a truck, upright frame members rigidly secured to the frame of the truck, a load elevating mechanism, rack bars mounted on the upright frame members, pinions engaging said rack bars, a power-operated means for actuating the load lifting mechanism comprising a shaft member rotatably mounted on the load lifting mechanism, cable winding elements on the shaft member and torque equalizing means connecting the shaft member and the winding elements.

32. A load elevating mechanism comprising an upright frame, load elevating means traversing the frame, a plurality of cables extending upwardly and passing over the frame adjacent its top, and rotatable stress equalizing means connecting the cables to the load elevating means, whereby the lifting load will be equally distributed to all the cables.

33. In a load elevating mechanism, the combination of an upright frame, load elevating means mounted thereon, a plurality of cables for moving the load, elevating means, rotatable stress equalizing means for distributing the load equally on the cables and reaction means actuated by the cables when taut and acting on said frame to move the load.

34. A load elevating mechanism comprising an upright frame, load elevating means traversing the frame, a pair of cables extending upwardly passing over the frame adjacent its top, load equalizing means connecting the cables to the load elevating means, and means for shifting the entire load to one of the cables when the other cable breaks.

In testimony whereof, I hereunto affix my signature.

CLYDE E. COCHRAN.
